Des. 189,256
Patented Nov. 15, 1960

189,256

LIGHTING FIXTURE

Emanuel Allan Rothman, Brooklyn, N.Y., assignor to
McPhilben Manufacturing Co., Inc., Brooklyn, N.Y., a
corporation of New York

Continuation of applications Ser. No. D. 54,543, Feb. 10,
1959, and Ser. No. D. 55,383, Apr. 6, 1959. This ap-
plication Apr. 8, 1960, Ser. No. 60,110

Term of patent 14 years

(Cl. D48—4)

Fig. 1.

Fig. 3.

Fig. 2.

Fig. 5.

Fig. 4.

Fig. 1 is a perspective view of a lighting fixture showing the new design;

Fig. 2 is a front elevation thereof;

Fig. 3 is a top plan view thereof;

Fig. 4 is a rear elevation thereof;

Fig. 5 is an elevation thereof as seen from the right of Fig. 2;

Fig. 6 is a perspective view of a modified form of the lighting fixture shown in Figs. 1 to 5 inclusive;

Fig. 7 is a front elevation thereof as shown in Fig. 6;

Fig. 8 is a top plan view thereof as shown in Fig. 6;

Fig. 9 is a rear elevation thereof as shown in Fig. 6;

Fig. 10 is an end elevation thereof as seen from the right of Fig. 7;

Fig. 11 is an elevation thereof as seen from the right of Fig. 8 with the front panel shown in open position.

This is a continuation of design application Serial No. 54,543, filed February 10, 1959, and Serial No. D-55,383, filed April 6, 1959, now abandoned.

I claim:

The ornamental design for a lighting fixture, as shown and described.
